UNITED STATES PATENT OFFICE.

DEWEY G. VANNORSDEL, OF KINGSLEY, IOWA.

END-GATE FASTENER.

Application filed March 28, 1923. Serial No. 628,163.

To all whom it may concern:

Be it known that DEWEY G. VANNORSDEL, a citizen of the United States of America, residing at Kingsley, in the county of Plymouth and State of Iowa, has invented 5 certain new and useful Improvements in End-Gate Fasteners of which the following is a specification.

My invention relates to end gate fasteners and its principal object is to provide a 10 device of this character which will eliminate the usual end gate rod and can be readily removed in close quarters where it would be impossible to take out an end gate rod.

15 Further the invention contemplates an end gate fastener particularly adapted for use on vertically sliding end gates and which includes the co-operating elements which will be readily arranged in operative position for locking the end gate to the wagon, and which when desired may be readily disengaged for permitting the end gate to be removed.

Further, the invention provides a device 25 of this character which may be used in conjunction with any type of end gate of the vertical slide type and which may be manufactured and sold at a nominal cost.

With the preceding and other objects and 30 advantages in view, the invention consists in the constructions, arrangements of parts and operations to be hereinafter specifically referred to, claimed and illustrated in the accompanying drawing, wherein—

35 Figure 1 is an end elevation of an end gate equipped with my invention;

Figure 2 is a side elevation of the same;

Figure 3 is a perspective of the device;

40 Figure 4 is a perspective of one of the elements used in the invention;

Referring in detail to the drawings wherein corresponding characters of reference denote corresponding parts thruout the several views, the numeral 5 designates a conventional wagon or truck provided with a vertically sliding end gate designated at 6. My improved fastener comprises a pair of rigid arms 7 secured to the opposite side walls of the wagon 5 and project beyond the same and provided with openings or bearings 8. A hasp is provided for each of the arms and each includes an obliquely disposed shank 9 having its lower end formed with a trunnion 10 which is journaled in 55 one of the bearings 8. The upper end of the shank 9 is formed with a rectangular yoke 11

adapted to receive the head 12 of a bolt 13, which extends transversely thru the end gate 6, the latter to be provided with nut 14 to retain this fastening in position. In order to retain the rectangular yoke 11 on the head the latter is provided with a vertically extending opening 12 which receives a pin 15 carried by a chain or other flexible element 16 secured to the end gate 6. When 60 it is desired to remove the end gate it is only necessary to disengage the pins from the head 12 and swing the hasps downwardly on their axis.

From the disclosure it will be seen that I 70 have provided a simple and inexpensive end gate fastener that may be associated with any end gate employing a vertical slide and may be readily associated with the same without altering the parts of the end 75 gate or wagon.

From the foregoing it will be seen that I have provided a simple, inexpensive and efficient means for carrying out the objects of the invention, and while I have particularly 80 described the means best adapted to perform the functions set forth, various changes in form, proportion and in the minor details of construction may be resorted to without departing from the spirit or sacrificing any 85 of the principles of the invention.

What I claim as new and desire to protect by Letters Patent is:

In a device of the class described, the combination with a wagon box body and a vertically slidible end gate therefor; of a fastening means for the end gate comprising rigid arms secured to the outer face of the side walls of said body and projecting beyond the rear end edges thereof, the projecting free ends of said arms being formed with bearings disposed in a horizontal plane below the upper edge of said end gate and above the transverse central plane of the wagon box body, said bearings being disposed in a vertical plane forward of the plane of the outer face of the end gate, a pair of hasps pivotally mounted at their inner ends in the bearings of the aforesaid arms and having upwardly and obliquely extending shank portions formed thereon, the extreme outer ends of said shank portions terminating in laterally disposed yokes, bolts mounted in said end gate adjacent the upper and side edges thereof, 100 nuts engaged with the inner ends of said bolts adapted for contact with the inner 105 110

face of the end gate, enlarged flat head portions formed on the outer ends of said bolts providing shoulders between the head portions and the bolts adapted to abut the outer face of the end gate to permit the head portions to project beyond the latter, said head portions being adapted for reception through the openings in said yokes and pro-

vided with lateral slots therein, the outer ends of said flat head portions being rounded, and pins adapted to be inserted through the slots in the head portions after the yokes have been applied thereto, as and for the purposes described. 10

In testimony whereof I affix my signature.
DEWEY G. VANNORSDEL.
